UNITED STATES PATENT OFFICE.

WALKER LEE CROUCH, OF NEW BRIGHTON, PENNSYLVANIA.

DESIGN FOR A FRAME FOR GAS-ENGINES.

SPECIFICATION forming part of Design No. 26,072, dated September 22, 1896.

Application filed June 24, 1896. Serial No. 596,803. Term of patent 14 years.

To all whom it may concern:

Be it known that I, WALKER LEE CROUCH, a citizen of the United States, residing at New Brighton, in the county of Beaver and State of Pennsylvania, have invented and produced a new and original Design for a Frame for Gas-Engines, of which the following is a specification, referring, however, to the accompanying drawing, forming a part thereof.

10 In the drawing is shown a perspective view of a gas-engine frame embodying my new and original design.

The leading features of my design consist in a gas-engine frame having a base, a round box-shaped case, and a cylinder above the case.

Referring to the drawing, A is the case, which is box-shaped or in the form of a short cylinder, having closed ends, and extending 15 from opposite sides are the base-pieces B B. Extending from the upper portion of the case

is the cylinder C, having a diameter substantially equal to the depth of the box-shaped case. Extending laterally from the cylinder near the top thereof and projecting above the 25 cylinder is a tube D.

From this general description of my design it will be understood that the essential features of the new design comprise the round box-shaped case, the base, and the cylinder 30 above the case.

What I claim is—

The design for frames of gas-engines substantially as above described and illustrated in the accompanying drawing. 35

In testimony whereof I have signed my name to this specification in the presence of two subscribing witnesses.

WALKER LEE CROUCH
